UNITED STATES PATENT OFFICE.

HENRY HIGGIN, OF NEWPORT, KENTUCKY.

ORNAMENTAL SCREW-BOLT HEAD.

SPECIFICATION forming part of Letters Patent No. 369,242, dated August 30, 1887.

Application filed December 17, 1886. Serial No. 221,877. (No model.)

To all whom it may concern:

Be it known that I, HENRY HIGGIN, of Newport, in the county of Campbell and State of Kentucky, have invented certain new and 5 useful Improvements in Ornamental Screw-Bolt Heads, of which the following is a specification.

My invention relates to an improved screw-bolt having an ornamental head. It is primarily adapted to be used as the center bolt of a prop-joint for carriage-tops, and the construction shown is adapted to that use; but it is obvious that it may be applied to many other uses.

15 The object of my invention is to rigidly attach the ornamental head to the shank or barrel of the screw. In the use of pivot-bolts for carriage-top joints a screw tap or nut is run on the threads chased on the end of the bolt, 20 and the tap holds the bolt in position while the end of the bolt is headed, to prevent it from turning or coming off. Difficulty is experienced in making an ornamental head and rigidly attaching it to the end of the bolt so that 25 it will not turn in the head when the tap is run on the thread.

30 My improvement overcomes this difficulty and produces a cheap ornamental screw-bolt, avoiding the use of solder, the construction of which is shown in the accompanying drawings, making a part of this specification, in which—

Figure 1 is a plan view of the base-plate. Fig. 2 is a sectional elevation of the screw bolt 35 and head attached to the base-plate. Fig. 3 is a similar view showing the locking-plate secured to the screw-head and base-plate. Fig. 4 is a modification of Fig. 3, showing the finishing-plate outside of the locking-plate. Fig. 40 5 is a sectional elevation of a modified form of ornamental head. Fig. 6 is a similar view of another modification, and Fig. 7 represents a modified form of bolt-head and locking-plate.

The several above views are enlarged beyond the ordinary size used in prop-joints for the purpose of illustrating that construction.

1 represents the shank or barrel of a bolt; 2, the head; 3, a slot milled in the head of the bolt.

50 4 represents the base-plate of the cap or head, which is pierced with a hole and receives the stem of the bolt, and it rests against the

under side of the head. The outer edge is shown bent or struck up slightly, so as to receive the lap of the finishing-plate.

55

5 represents the locking-plate, which is provided with a flute or corrugation, *a*, struck in the center of the plate, which nests in the groove 3 of the bolt-head.

In Fig. 3 the plate 5 is doubled at the outer edge over, around, and under plate 4. The lap 6 draws plates 4 and 5 rigidly together and secures them to the head of bolt 2, so that the bolt cannot turn independent of the cap. When it is desired to have the indentation out 65 of sight, I provide an additional plate, 7, to go outside of the plate 5, which latter is made of the same diameter as base-plate 4, and the lap 6 for securing plates 4 and 5 together on the bolt-head is formed by turning the edge of 70 plate 7 over, instead of plate 5, as shown in Fig. 3. The depression *a* in plate 5 is thus hid from view. 8 and 9 represent beads or 75 ornamentations struck up in plate 7. Sometimes it is desirable to use a leather or other fancy finished covering-plate for the head of the bolt. Such a construction is shown in Fig. 5.

The plates 4 and 5 are constructed as shown in Fig. 4. 10 represents the ornamental covering of the bolt-head, and the three parts 4, 80 5, and 10 are secured together by the metal clamp 11, which is compressed by suitable dies upon the peripheral edge of the bolt-head.

Fig. 6 represents a modification of Fig. 3, the only difference being that the under plate, 4, 85 5, is bent around and lapped upon the top plate, 5, instead of having the top plate lapped over upon the bottom plate.

The object of the slot 3 in the bolt-head and the indentation in the plate, *a*, is to prevent 90 the head of the bolt from turning between the plates 4 and 5, and of course a projection on the bolt-head nesting in a corresponding cavity in plate 5 would accomplish the same result. Fig. 7 represents such a modification 95 with the projection upon the bolt-head and a cavity in the locking-plate 5. This projection is represented as a many-sided boss on the top of the bolt-head, fitting in a correspondingly-shaped cavity formed in plate 5, which is preferably covered by plate 7, and the plates secured together, as shown in Fig. 4; but I do not limit myself to the form or number of 100 teats and grooves or projections and cavities

formed on the bolt-head and locking-plate 5, each the counterpart of the other and nesting together to prevent the turning of the bolt-head between the plates 4 and 5, as I deem the 5 form shown in Figs. 4 or 5 the best.

It will be observed that the head of the screw-bolt is secured by the clamping of the plates 4 5 together, by the overlapping of one plate upon the other, and by the indentation and 10 projection in the head and the plate, respectively. To secure these results the head of the bolt is made large and thick, so that the strain of the two plates shall be sufficient to prevent the head from turning between them, and the 15 indentation and projection are of sufficient distance from the axial center of the bolt to prevent the breaking off of the same. Were the thin metallic plate indented at the center only, the strain upon the circumference of the 20 head would bend or double the plate; but by having the large head, with the nesting projection and indentation, a considerable dis-

tance from the axial center of the bolt this difficulty is avoided.

Having described my invention, I claim as 25 new—

An ornamental bolt-head composed of the head 2 and the plates 4 5, embracing the upper and lower sides thereof, and clamped together by the overlapping of one plate upon 30 the other, one of said plates being locked to the head of the bolt by means of an indentation and a projection upon the head of the bolt and inner face of the plate, respectively, whereby the parts are rigidly secured together and 35 the head of the bolt is anchored to said plates, substantially as herein specified.

In testimony whereof I have hereunto set my hand.

HENRY HIGGIN.
